CONVERSION OF HYDROCARBON OILS

Joseph Mason Barron, Port Arthur, Tex., assignor, by mesne assignments, to The Texas Company, New York, N. Y., a corporation of Delaware

Application February 25, 1941, Serial No. 380,443

1 Claim. (Cl. 196—49)

This invention relates to a combination thermal cracking and coking and catalytic cracking process for the production of a maximum yield of high antiknock gasoline or motor fuel.

The invention contemplates a method of processing in a unitary operation relatively light charging stocks adapted for catalytic cracking and heavier charging stocks adapted for coking. In accordance with the invention a stock suitable for catalytic cracking, such as gas oil, is subjected to catalytic cracking while a heavier stock such as a crude petroleum residual stock is subjected to coking to produce a coke residue and volatilized constituents which are subjected to thermal cracking. The invention, furthermore, contemplates the coking of residual components of the catalytically cracked products and the thermal cracking of constituents volatilized in the coking thereof.

In accordance with the invention a charging stock such as crude petroleum or topped crude is subjected to distillation in a common zone into which the products of the catalytic cracking are introduced for distillation. The evolved vapors are fractionated to separate out fractions, comprising constituents of the crude oil and of the catalytically cracked products, which are suitable for catalytic cracking and these fractions are directed to the catalytic cracking zone. The mixture of residual components of the crude petroleum and catalytically cracked products is subjected to coking to form a coke residue and vapors. The vapors from the coking operation are fractionated to separate the heavier components including tarry constituents from lighter components such as constituents of the gas oil and kerosene boiling ranges which latter constituents are subjected to thermal cracking.

For the purpose of more fully disclosing the invention reference is now had to the accompanying drawing which is a flow diagram illustrating apparatus adapted for the practice of the invention.

Referring to the drawing charging stock such as crude petroleum or topped crude is charged by a pump 10 to a heating coil 11 wherein the oil is heated to a desired distilling temperature. A portion or all of the heating may be supplied by hot products of the system and a portion or all of the heating may be obtained by furnace heat. The charging stock heated to a desired distilling temperature is directed to a stripping and fractionating tower 12 and is preferably discharged above a tray 13 provided with a run-back line 14 for directing the unvaporized residue to a lower

section of the tower which receives hot products introduced through a line 15 from a source which will be presently explained. The tower 12 is provided with conventional fractionating elements and with cooling and refluxing means to effect the desired fractionation of the vapors which separate from the residue collecting in the bottom of the tower. The overhead vapors from the tower pass to a condenser coil 16 and the distillate is collected in a distillate receiver 17. The tower is preferably equipped with a plurality of trays 18 for collecting a plurality of condensate fractions. Lines 19 extend from the several trays to a header 20 leading to a distillate tank 21 so that a selection may be made with respect to the fractions collected in the distillate tank.

A pump 22 draws distillate from the tank 21 and directs it through a line 23 to a heating coil 24 positioned in a furnace 25 which discharges the heated oil to a catalytic cracking chamber 26. Usually a plurality of catalyst chambers are employed so that the catalyst may be periodically revivified or regenerated without interrupting the continuity of the process.

The catalyst disposed in the chamber 26 consists advantageously of a synthetic silica-alumina type of catalyst. Various acid-treated and metal-substituted clays such as the Super-Filtrols and acid-treated and metal-substituted natural or artificial zeolites, such as the artificial zeolite known as Doucil may be employed. Various metals such as uranium, molybdenum, manganese, lead, zinc, zirconium, nickel and the like, may be substituted in the clays or zeolites. Likewise, the combination of certain acid-treated active clays of the character of Filtrol, together with added proportions of alumina or silica or both may be employed. Alumina alone may be used under certain conditions. The synthetic alumina catalysts can be improved by the addition of other constituents such as zirconium oxide or molybdenum oxide.

Line 15 communicates with the catalyst case 26 and serves to direct the products of the catalytic cracking to the distilling tower 12. The residual components of the catalytically cracked products collect as liquid residue in the lower portion of the tower 12, the stripped crude residue from tray 13 being combined therewith, while the separated vapors pass upwardly through the tower being combined with the crude oil vapors and subjected to fractionation therein.

The residue consisting of a mixture of residual components of the catalytically cracked products and of the crude petroleum is withdrawn

from the tower 12 by a pump 27 and directed through a line 28 to a heating coil 29 disposed in a furnace 30 wherein the residual constituents are heated to a cracking temperature and to a temperature sufficient to support coking upon being discharged into a coking chamber 31. In practice, a plurality of coking drums are used so that one or more drums may be removed from the line and the coke removed while maintaining one or more drums continuously in the line and the continuity of the complete combination process maintained.

The evolved vapors from the coke drum 31 pass to a dephlegmator 32 in which the vapors are given a primary dephlegmation to separate out the heavier constituents including particularly the tarry component of the vapors evolved in the coking operation. Suitable refluxing means not shown may be provided for the tower 32. The uncondensed vapors which include gas oil constituents as well as gasoline constituents pass to a condenser 33 and the distillate is collected in a receiving drum or gas separator 34.

Distillate from receiving drum 34 is directed by a pump 35 through a line 36 to the fractionator 37 of the thermal cracking unit of the process. The thermal cracking unit includes a heating coil 38 disposed in a furnace 39 and reaction chambers 40 and 41 which are preferably insulated against heat loss. A transfer line 42 conducts the heated effluent from the coil 38 to the reaction chamber 40 and the transfer line 43 conducts the effluent from chamber 40 to chamber 41 wherein separation of vapors from liquid residue takes place, the separated vapors passing through line 44 to the fractionating tower 37 and the residue passing through a line 45 to the dephlegmator 32. Normally the pressure is reduced in chamber 32 as compared to the pressure obtaining in reaction chamber 41 so that chamber 32 serves not only as a primary dephlegmator for the coke still vapors but also as a flashing zone for the residue from the thermal cracking zone. The fuel oil product comprising the flashed thermally cracked residue and the tarry component of the coke still vapors is withdrawn as a liquid fuel oil product through the line 46.

The tower 37 is provided with conventional fractionating elements and with suitable cooling and refluxing means not shown. The cracked vapors from the reaction chambers are subjected to fractionation and the coke still distillate introduced into the tower is subjected to redistillation and refractionation so that a composite reflux condensate consisting of constituents from both the coking and thermal cracking operations is collected in the tower 37 and this reflux condensate is directed by a pump 47 through a line 48 to the heating coil 38 wherein the oil is raised to a cracking temperature and passed to the reaction chambers 40 and 41 wherein cracking temperatures under superatmospheric pressures are maintained. The overhead vapors from the tower 37 pass to a condenser 49 and the distillate comprising gasoline constituents produced as a result of the thermal cracking and coking operations is collected in a receiving drum or gas separator 50.

In a modification of the invention a portion of the reflux condensate flowing to the heating coil 38 of the thermal cracking unit may be diverted through a by-pass line 51 to the line 23 and passed thence to the heating coil 24 and catalyst case 26.

In another modification of the invention a portion of the heated effluent from the heating coil 38 may be diverted through a by-pass line 52 so as to combine hot products from the heating coil 53 38 with the stream of products from the heating coil 24 passing to the catalyst case 26.

In practicing the invention crude oil or a topped crude is preheated by heat exchange with hot products of the system or otherwise heated to temperatures of the order of 500° F. to 700° F. and discharged into the distilling tower. Normally, the crude oil constituents will receive additional heat to further raise the temperature in the tower due to the influx of hot products from the catalytic cracking zone. The resultant mixture of bottoms of the catalytic cracking and crude petroleum residual constituents is passed to the heating coil of the coking unit wherein it is heated to temperatures upwards of 850° F. and generally around 900° F. which temperatures will support coking in the coking drum. Low pressures of approximately 15 lbs. to 40 lbs. per square inch are preferred in the coking drum and it is likewise preferred to have no material drop in pressure between the heating coil outlet and the coking drum. Cracking is carried on in the thermal cracking zone under any suitable temperature-pressure conditions for thermal cracking, although usually pressures of 200 lbs. or higher are employed in the reaction chambers. The pressure in the combination flash tower and coke still dephlegmator is very materially lower than that in the thermal reaction zone. Normally, pressures of about 15 to 25 lbs. are employed. The catalytic cracking operation is advantageously conducted at pressures not materially over 100 lbs. and in fact, with the catalysts disclosed herein, is best conducted at lower pressures down to approximately atmospheric pressures.

In an example of the invention a crude petroleum charge is distilled with the aid of hot products from the catalytic cracking zone and the combined catalytically cracked gasoline and straight run gasoline is collected as a product of the process. The mixture of reduced crude and residual constituents from the catalytic cracking is heated to a temperature of 910° F. and discharged into the coke drum wherein a pressure of 20 lbs. is maintained. The coke still gas oil is subjected to thermal cracking with recycling at a temperature of about 910° F. in the reaction chambers under 400 lbs. pressure. The thermally cracked residue is expanded into the coke still dephlegmator wherein a pressure of 15 lbs. is maintained. A mixture of straight-run and catalytically cracked gas oil is heated to a temperature of 950° F. and is charged into the catalyst case wherein a pressure of 10 lbs. is maintained.

It is advantageous to direct a portion of the cycle condensate from the thermal cracking operation to the catalytic cracking operation, since the thermally cracked product constitutes a suitable charging stock for the catalytic cracking unit. In accordance with the invention this cycle stock from the thermal cracking unit may be combined with the mixture of straight-run and catalytically cracked gas oil passing to the heater of the catalytic cracking unit. In some cases the vapors from the thermal cracking operation may be fractionated to obtain, in addition to the gasoline distillate, a heavier reflux condensate and a lighter or intermediate reflux condensate, the heavier reflux condensate being cycled to the

thermal cracking zone and the lighter or intermediate condensate being directed to the catalytic cracking zone. Another advantageous operation is to divert a portion of the stream from the heater of the thermal cracking unit to the catalytic cracking chamber.

While I have described a particular embodiment of my invention for purposes of illustration, it should be understood that various modifications and adaptations thereof which will be obvious to one skilled in the art, may be made within the spirit of the invention as set forth in the appended claim.

I claim:

The combination thermal and catalytic cracking process that comprises introducing the catalytically cracked products and crude petroleum charging stock into a vaporizing and separating zone wherein vaporization of a portion of the charging stock takes place, subjecting resultant separated vapors to fractionation to separate gasoline distillate from higher boiling reflux condensate, directing said higher boiling reflux condensate in admixture with additional reflux condensate formed as hereinafter specified to a catalytic cracking zone wherein the oil is subjected to catalytic cracking, passing the resultant prod-

ucts of the catalytic cracking to said vaporizing and separating zone as aforesaid, directing the resultant residue from said vaporizing and separating zone to a thermal coking zone wherein the residue is subjected to coking to produce a coke residue, separately subjecting the evolved vapors from the coking zone to fractionation to separate higher boiling fractions from a lower boiling condensate, introducing said lower boiling condensate into another fractionating zone for refractionation in contact with vapors therein and wherein fractionation to separate gasoline constituents from higher boiling reflux condensate takes place, directing a portion of the reflux condensate from the latter fractionating zone to a thermal cracking zone wherein the oil is subjected to cracking conditions of temperature and pressure to effect thermal cracking, separating the resultant products of the thermal cracking into vapors and residue, passing the separated vapors to the latter fractionating zone and utilizing another portion of the reflux condensate from the latter fractionating zone as the additional reflux condensate being passed to the catalytic cracking zone.
